assignor to Gustav Schwarz G. m. b. H., Berlin-
Waidmannslust, Germany, a limited company
of Germany

Application July 16, 1935, Serial No. 31,643
In Germany July 20, 1934

7 Claims. (Cl. 170—173)

My invention relates to improvements in propellers, and more particularly in propellers for air craft. One of the objects of the improvements is to provide a propeller, in which the blade or blades are rigidly fixed to the hub. Another object of the improvements is to provide a propeller in which the sleeve or sleeves in which the blade or blades are fitted may be made comparatively short, and in which therefore the mass of the hub is reduced. With these objects in view my invention consists in constructing the hub with a longitudinally slotted sleeve having the blade fitted therein and clamping the said sleeve by suitable means such as screws on the blade, the slot of the sleeve extending from the outer end thereof inwardly and beyond the end of the portion of the blade engaged thereby so far that the sleeve is in clamping engagement with the whole portion of the blade engaged thereby.

For the purpose of explaining the invention several examples embodying the same have been shown in the accompanying drawing in which the same reference characters have been used in all the views to indicate corresponding parts. In said drawing

Fig. 1 is a sectional plan view showing the hub of the propeller, a part of the propeller shaft and the inner ends or roots of the blades.

Fig. 2 is an elevation of the propeller shown in Fig. 1.

Fig. 3 is a sectional elevation taken on the line 3—3 of Fig. 1.

Fig. 4 is a sectional plan view similar to the one illustrated in Fig. 1 and showing a modification in which the length of the sleeve and the portions of the blades engaged thereby are reduced.

Fig. 5 is a sectional plan view showing another modification in which the sleeve is formed with a flange adapted to be fixed to the propeller shaft,

Fig. 6 is an end elevation of Fig. 5.

Fig. 7 is a sectional plan view showing a propeller having three blades.

Fig. 8 is an end view of the propeller shown in Fig. 7, and

Fig. 9 is a sectional plan view of a propeller in which the construction of the blades and the sleeves carrying the same is the same as that shown in Figs. 7 and 8, the manner of mounting the said sleeve on the propeller shaft being different from what has been shown in Figs. 7 and 8.

In Figs. 1 to 3 I have shown a propeller which comprises two oppositely arranged blades 7. The hub of the said propeller comprises a sleeve comprising two integral portions 1, 1 and a hub member 9 extending transversely through the said

sleeves, the said hub member 9 being fixed to the tapering end 10 of a propeller shaft 8 by means of a cap 12 screwed on the screw-threaded end 11 of the shaft, the sleeve 1, 1 being formed at its outer end with a circular cut-out portion 13 for the passage of the hub member 9 therethrough. The sleeve 1, 1 is formed with a longitudinal slot 2, 2 extending from end to end and including the circular cut-out portion 13. At the opposite sides of the said slots the walls of the sleeve are formed with eyes 3 for the passage of clamping bolts 4 therethrough.

The sleeves 1, 1 have the roots 6, 6 of the blades 7, 7 fitted therein, and they are formed with internal screw-threads engaged by corresponding screw-threads of the roots 6, 6. The blades are fixed in position by means of the said screw-threads and the clamping bolts 4 by means of which the sleeves are held in clamping engagement with the roots, the elasticity of the sleeves being sufficient to permit such clamping. By having the slot 2, 2 extending continuously all through the length of the sleeve 1, 1 a uniform pressure is exerted by the sleeve on the roots all over the length thereof. Therefore the blades are securely fixed in position within the sleeve.

By thus clamping the sleeve on the roots 6 all over the length thereof I am enabled to reduce the length of the sleeve 1, 1 as compared to the construction shown in Figs. 1 to 3. In Fig. 4 I have shown a modification in which the length of the sleeve has thus been reduced, and in which a single clamping bolt is provided for each root. Otherwise the construction of the hub is the same as has been described with reference to Figs. 1 to 3, and the same letters of reference have been used to indicate corresponding parts. The roots of the blades and the sleeves which are reduced in length have received the reference characters 46 and 41 respectively, and the clamping bolts only one of which is provided for each blade have received the reference character 44. By providing a blade root of large diameter the construction may be adapted to the forces developed in the hub by the operation of the propeller.

In Figs. 5 and 6 I have shown a modification in which the hub is fixed to the propeller shaft 8 in a different way. The sleeve 51 in which the roots 56 of the propeller blades are fitted is formed with a longitudinal slot 52 extending all over the length of the sleeve. The sleeve is formed with internal screw-threads corresponding to the screw-threaded roots 56 of the blades and two eyes 53 and clamping bolts 54 are provided for clamping the sleeve on the roots 56.

At the side opposite to the slot 52 the sleeve 51 is formed with a flange 15 fixed to a flange 14 formed at the end of the propeller shaft 8 by means of screws 16.

5 As appears from the figures the length of the sleeve 51 is further reduced as compared to the length of the sleeve 41 shown in Fig. 4, and yet the strength of the construction is not reduced, because the active length of the sleeve which is 10 in clamping engagement with the roots 56 is not reduced in length. Also in this case the roots of the blades and the sleeve are formed with corresponding screw-threads.

In Figs. 7 and 8 I have shown a propeller which 15 is provided with three blades. The construction of the hub is similar in principle to that shown in Figs. 5 and 6, the propeller shaft 8 being formed with a flange 14 having a flange 15 of the hub fixed thereto by screws 16. The hub is 20 formed with three integral sleeves 71 arranged so as to radiate from the axis of the propeller, and at the outer side of the hub each sleeve is 25 formed with a longitudinal slot 72 extending all over the length of each sleeve and to a circular cut-out portion 77 thereof. Adjacent the said slots the sleeves are formed with flanges 73 formed with bores for the passage of pairs of clamping screws 74 therethrough. The roots of the blades 30 and the sleeve are formed with corresponding screw-threads 76. It will be readily understood that the sleeves are pressed into clamping engagement with the whole length of the roots.

In Fig. 9 I have shown a propeller in which 35 the construction of the hub is the same as has been described with reference to Figs. 7 and 8 and the same numerals of reference have been used to indicate corresponding parts. However, the hub is intended to be fixed to a propeller shaft 8, 10 which extends through the same, and for 40 this purpose a tubular intermediate member 19 is provided which is formed with a flange 18 fixed to the flange 15 of the hub, the said tubular member 19 fitting on the tapering end 10 of the propeller shaft and being fixed in position there- 45 on by means of the cap screw 12.

By providing the said intermediate member the hub may be mounted at will either on a propeller shaft formed with a flange 14 or on a propeller shaft formed with a tapering end 10.

50 I claim:

1. A propeller, comprising an integral longitudinally slotted sleeve adapted to be fixed to a propeller shaft, a blade fitted with its root in said

sleeve, and means to clamp said sleeve on said root, the slot of said sleeve extending in the body of the sleeve from the end thereof and beyond the root of the said blade so far that the sleeve is in substantially uniform clamping engagement 5 with the root all over the length thereof.

2. A propeller, comprising an integral sleeve adapted to be fixed to a propeller shaft and formed with a longitudinal slot extending from end to end over the length of the whole structure, 10 a blade fitted with its root in said sleeve, and means to clamp said sleeve on the whole part of the root of the blade engaged thereby.

3. A propeller, comprising an integral sleeve adapted to be fixed to a propeller shaft and 15 formed with a longitudinal slot extending over the whole length thereof, blades fitted with their roots in opposite ends of said sleeve, and means to clamp said sleeve on the whole parts of the roots of the blades engaged thereby. 20

4. A propeller, comprising a plurality of sleeves made integral and arranged so as to radiate from an axis disposed transversely thereof and each formed with a longitudinal slot, said slots extending over the whole length of said sleeves 25 and merging into one another at the inner ends of said sleeves across the central portion of the structure, said sleeves being adapted to be fixed to a propeller shaft, blades fitted in said sleeves, and means to clamp said sleeves on the whole 30 length of the blades engaged thereby.

5. A propeller as claimed in claim 3, in which the longitudinal slot is provided at the front side of said sleeve and comprises an enlarged portion 35 at its middle located in axial alignment with the part of the sleeve which is to be fixed to the propeller shaft, and means accessible through said enlarged portion for fixing said sleeve to the propeller shaft.

6. A propeller as claimed in claim 3, in which 40 the longitudinal slot is provided at the front side of said sleeve and comprises an enlarged portion at its middle, and in which the sleeve is formed with a hub member adapted to be fixed to the propeller shaft and extending transversely 45 through the sleeve and towards said enlarged portion.

7. A propeller as claimed in claim 2, in which 50 the longitudinal slot is provided at the front side of said sleeve, and in which the said sleeve is constructed at its rear side for being secured to the propeller shaft.

MANFRED GRABARSE.
